UNITED STATES PATENT OFFICE.

CARL SCHMIDT, OF WIESBADEN, GERMANY.

BUTTON.

SPECIFICATION forming part of Letters Patent No. 763,512, dated June 28, 1904.

Application filed July 24, 1903. Serial No. 166,876. (No model.)

To all whom it may concern:

Be it known that I, CARL SCHMIDT, a subject of the German Emperor, and a resident of Wiesbaden, Germany, have invented a certain 5 new and useful Improvement in Buttons, of which the following is a description.

The object of the present invention relates to a button the fastening whereof is obtained by means of a metal wire twisted and placed 10 inside the button.

A species of this invention is given by way of example in the annexed drawings, in which—

Figure 1 is a cross-section of the button before the metal wire is twisted. Fig. 2 shows a similar section, but after the wire is twisted. Fig. 3 is a sectional view of a detail. Figs. 4 and 5 show a side and a plan view of the plate provided with two metal wires.

A truncated and cylindrical portion *c* (shown in detail in Fig. 3) is arranged in the bottom part of an ordinary metal button made in two parts, a hollow top section or cup *a* and a perforated base-section *b*. This portion *c* can 20 turn freely inside the button *a* *b*. To the center of the top cup *a* of the hollow button the metal wire *d* is fixed, and projecting toward the inside passes through the bottom *c* by a central hole *c'*, Fig. 3. Upon the right and 25 left of this spindle and at equal distances from the same the cup *a* is provided upon each side with a hole *e*. These holes are directly opposite two holes *f*, *f'* of a corresponding size made in the bottom of the piece *c*. When it is required to fasten the button, the usual three 30 needles are replaced by a pointed fork *g*, made of metal wire fixed upon a metal plate *h*. This

fork *g* is pushed through the material *i* of the garment from the inside toward the outside. The projecting ends are first placed in the 40 holes *f*, then in the holes *e*, so as to cause them to project from the cup *a* of the button. Then by turning the button *a* *b* the branches *g'* of the fork wind round the center spindle, and thus cause the fixture of the button upon 45 the disk *h* and upon the material. Owing to the branches *g'* of the fork being shortened while being wound upon the pin *d*, their ends finish by entering inside the button, thereby leaving the surface of the same perfectly 50 smooth.

Having now fully described my invention, what I claim, and desire to secure by Letters Patent, is—

A button comprising a perforated base-section, a hollow top section revolvably secured to said base-section and having perforations adapted to register with two of the perforations in the base-section, a central spindle secured to the inner part of the revolvable section and having its opposite end engaging with a central perforation in the base-section, a disk provided with projecting wires adapted to pass through the fabric and also through perforations in the base-section and the revolvable section, whereby a turning of the revolvable section will cause said wires to be coiled around the central spindle and the ends thereof to be drawn into the hollow button portion, substantially as described.

CARL SCHMIDT.

In presence of—

H. W. LINGEL,

HENRY HOLLMANN.
